ABSTRACT: A two-piece key constructed to have substantially less bulk and weight than conventional keys so that a number thereof can be carried without inconvenience providing an elongated blade having an integral shank and a key manipulating member releasably connectable to the shank to provide sufficient turning leverage for the blade to permit ready manipulation of the key during use with a plurality of similar key blades being conveniently carried and selectively employed with the single key manipulating member.

FIG. 1.FIG. 2.FIG. 3.

AKIRA TAJIRI
INVENTOR

Huebner & Horrel
ATTORNEYS

TWO-PIECE KEY

BACKGROUND OF THE INVENTION

It is the usual practice to carry a plurality of conventional keys on a single key chain. If the key chain has a relatively large number of keys disposed thereon, the substantial bulk and weight of the keys make them difficult conveniently to carry. The principal weight in conventional keys is in the handles which are relatively large to provide turning leverage, to provide key identification, to designate key blanks for reproduction purposes, and for aesthetic purposes. It was recognized that the weight and bulk of such conventional keys could be substantially reduced if the handle portions thereof were removable when not in use.

SUMMARY OF THE INVENTION

Accordingly, it is an object of the present invention to provide an improved, relatively lightweight key.

Another object is to provide such an improved, lightweight key which affords substantially less bulk than conventional keys.

Another object is to provide an improved, lightweight key of the character described which has a removable handle.

Another object is to provide an improved, lightweight key having a separable blade and handle so that a plurality of such key blades can be mounted on a single key chain and selectively employed with the single handle on the key chain.

Other objects and advantages of the present invention will subsequently become more clearly apparent upon reference to the following description and accompanying drawing.

BRIEF DESCRIPTION OF THE DRAWING

FIG. 1 is an elevational view of a two-piece key embodying the principles of the present invention having a separable blade and handle disposed in a separated condition on a common key chain.

FIG. 2 is an elevational view of the blade and handle assembled for use on the key chain.

FIG. 3 is a perspective of the blade and handle on the key chain aligned prior to assembly.

DESCRIPTION OF THE PREFERRED EMBODIMENT

Referring more particularly to the drawing, a two-piece key embodying the principles of the present invention is shown providing an elongated key blade 10 constructed of a substantially flat key blank having a plurality of elongated, longitudinally extended grooves 11 and tumbler actuating ridges and notches 12 edgewardly formed therein in the usual manner. The blade includes an integral, substantially square shank 14 having only a slightly wider dimension than the blade. A key chain receiving opening 15 is substantially centrally formed through the shank.

An elongated key chain 16 of conventional construction is adapted to be passed through the opening 15 in the shank 14 with the ends of the key chain interconnected by a conventional locking device 17 to preclude inadvertent removal of the blade 10 therefrom.

A separate handle 20 is provided for assembly with the blade 10 to permit the key to be manipulated in the usual manner. The handle is of substantially rectangular configuration and may be formed of molded plastic or of the same material as the blade 10. The handle provides opposite front and rear sides 22 and 23, respectively. A substantially square relatively narrow socket 25 is formed in the front side 22 of the handle and terminates just short of the rear side 23 thereof and is of a size only slightly larger than the shank 14 of the key blade 10. A notch 26 is formed through the handle 20 in a direction substantially right-angularly related to the plane of the socket 25 and substantially centrally thereof in alignment with the opening 15 in the shank 14 of the blade 10. This permits full insertion of the shank into the socket with the key chain 16 passing through the notch 26.

An elongated mounting tab 28 is endwardly extended from the handle 20 to provide a key chain receiving hole 30 for mounting the handle on the same key chain as the key blade 10. As best shown in the dashed lines of FIG. 1, a plurality of key blades substantially similar to the key blade 10 can be concurrently mounted on the single key chain 16.

OPERATION

- 10 The operation of the described embodiment of the subject invention is believed to be clearly apparent and is briefly summarized at this point. As described, a plurality of the key blades 10 can be mounted on the single key chain 16 with the substantially smaller shank 14 thereof being substituted for 15 the conventional, substantially larger handle which represents more than a 50 percent reduction in the weight of each key. When a large number of keys is disposed upon the key chain, the aggregate savings in weight and bulk is appreciable.
- During use, the selected key blade 10 is easily manipulated 20 to insert the shank portion 14 into the socket 25 of the handle 20. During such assembly, the portion of the key chain 16 passing through the hole 15 in the shank 14 slides easily into the notch 26 in the socket without requiring either the key blade 10 or the handle 20 to be removed from the key chain.
- 25 Thus assembled, the handle provides sufficient turning leverage for manipulation of the key within its corresponding lock cylinder, not shown. Thereafter, the key blade 10 is readily removable from the lock by the imposition of an outward pulling force upon the key chain passing through the shank of the blade. Furthermore, various means may be provided for identifying different keys on the key chain by providing notches or other distinctive marks along the sides or ends of the key blades, by utilizing variously colored keys, and by 30 providing distinctive length and shape to the key blades.

In view of the foregoing, it is readily apparent that the structure of the present invention provides an improved, two-piece key which affords substantially less weight and bulk than conventional keys. The releasable handle structure of the present 40 invention permits a relatively large number of keys to be mounted upon a single key chain with a single handle also disposed upon the same chain for alternate use with selected keys.

Although the invention has been herein shown and 45 described in what is conceived to be the most practical and preferred embodiment, it is recognized that departures may be made therefrom within the scope of the invention.

I claim:

1. A two-piece key comprising an elongated blade having an 50 integral shank providing a key chain receiving opening; a key manipulating handle having a socket into which said shank of the blade is releasably slidably receivable to provide turning leverage for the blade and to permit ready manipulation of the key during use so that a plurality of similar key blades can be 55 conveniently carried and selectively employed with the single handle, said handle further providing a key chain receiving opening therein in spaced relation from said socket; a key chain extendible through said opening in the handle and through the openings of a plurality of such shanks; and means in said handle to accommodate the portion of the key chain passing through the shank of a selected blade to permit unrestricted assembly of the shank into the socket of the handle.
2. The two-piece key of claim 1 in which said handle is constructed in a substantially flat rectangular form with said socket being similarly formed and disposed in the plane of the handle, and an edgewardly disposed notch extended through the handle in a plane substantially perpendicular to said plane of the socket and aligned with said opening in the shank of the 65 blade when the shank is inserted into said socket of the handle to accommodate the portion of said key chain passing through said opening in the shank to permit assembly of the selected blade and handle while both are mounted on the key chain.
3. The combination of a plurality of elongated blades each 70 having a lock operating portion and an integral shank, a

manipulating handle having a socket into which the shanks of the blades are individually releasably receivable to permit selective utilization of the blades in the handle and the application of turning leverage thereto by the handle, and means interconnecting the handle and blades in a unitary assembly 5 accommodating relative movement of the blades and handle for selective mounting of the blades in the handle while interconnected in said assembly.

4. The combination of claim 3 in which said means includes openings through the shanks of said blades, an opening 10

through said handle, and a key chain extended through said openings in interconnecting relation between said handle and said plurality of blades.

5. The combination of claim 4 in which said means further includes a notch in said handle communicating with said socket therein to accommodate the portion of said key chain passing through said opening in the shank of the blades during said selective mounting of the blades in the handle.
